UNITED STATES PATENT OFFICE.

DALLAS F. GRAHAME, OF WESTMOUNT, QUEBEC, CANADA, ASSIGNOR TO RILEY STOKER CORPORATION, OF WORCESTER, MASSACHUSETTS, A CORPORATION OF MASSACHUSETTS.

STOKER-RAM DRIVE.

Original application filed January 28, 1922, Serial No. 532,429. Patent No. 1,632,401, dated June 14, 1927.

Divided and this application filed June 10, 1927. Serial No. 197,833.

In the installation of underfeed stokers in many plants, it is desirable (as pointed out in my co-pending application, Serial No. 532,429, filed January 28, 1922, now 5 Patent 1,632,401, June 14, 1927 of which this application is a division) that the ram or rams for feeding the coal shall be operated by what is called a "mechanical drive", rather than by a steam-cylinder piston, and 10 the general purpose of my invention is to provide an advantageous equipment to this end. It is also desirable that the periodicity of operation of the ram or rams shall be controllably variable so that a given ram 15 may feed fuel at different appropriate rates to meet varying demands. Some installations require that this periodicity of ram-operation shall be automatically controllable by a pressure-responsive device which is 20 acted on by steam generated from the boiler being served by the stoker. In practically all installations it is required that the periodicity of operation of the ram, or of each ram individually, be manually settable. In 25 either event the time taken by a cycle of operations of any ram is variable. I regard it as very advantageous to secure rather rapid operation of the ram plunger on both its feed stroke and its return stroke, making the 30 speed of ram travel uniform, regardless of variations in time consumed by a cycle of ram-operations, and also advantageous to drive each ram individually from an electric motor that is associated with that particular ram by connections which are mechanically 35 compact and simple and which permit overrunning of the electric motor and a substantially loadless "pick up" of the motor.

Attainment of these and other desiderata 40 by simple, rugged, efficient structures and by advantageous correlation of the devices employed, are among the objects of my invention sought and attained, and other and further objects will become apparent from the 45 following description taken in conjunction with the accompanying drawings and setting forth one desirable embodiment of my invention for purposes of full disclosure although, as will become apparent, many 50 changes may be made in the embodiment of the invention without departure from the spirit of the invention and within the scope of the appended claims.

In the drawings, Figure 1 is a schematic

elevation of an underfeed stoker drive for 55 a two-unit plant, installed in accordance with my invention, the appliances being diagrammatically illustrated and some duplicate parts being spread out, in diagrammatic fashion, for convenient visibility;

60 Fig. 1^a is a plan view of the stoker rams and their driving motors;

Fig. 2 is a longitudinal vertical section, 65 with parts in elevation, of an individual screw drive for one of the rams;

Fig. 3 is a front end elevation thereof;

Fig. 4 is a cross-sectional detail on line 4-4 of Fig. 2;

Fig. 5 is a cross-sectional detail on line 5-5 of Fig. 2;

Fig. 6 is an enlarged perspective view of 70 one of the pawls of the nut shown in Fig. 4;

Fig. 7 is a plan view of a switch structure for controlling the operation of the electric motor, with parts broken away;

Fig. 8 is an end elevation thereof, with 75 parts broken away;

Fig. 9 is a fragmentary detail of parts of said switch; and

Fig. 10 is a side elevation, with parts 80 broken away, of the ratchet and pawl mechanism of said switch, as viewed on line 10-10 of Fig. 8.

In the drawings, 15 indicates generally a furnace to which fuel is supplied by an underfeed stoker involving one or more feed-ram structures having appropriate feed-hoppers. Two such feed-structures are diagrammatically indicated at 16 and 16', Fig. 1, although any suitable number may be employed. As usual, the fuel is to be burned under forced air-draft, supplied as by a fan 17, for the generation of steam in a suitable boiler, a fragment of which is indicated at 18.

85 In many commercial installations it is desirable to make such provision that, as the steam-pressure drops, the supplies of fuel and of air to the stoker shall, automatically, be augmented, and vice versa. The air-draft part of this regulating action may be 90 effected in well-known fashion and I have diagrammatically illustrated well-known appliances for this purpose. Thus, in the specific illustration, the boiler 18 has a steam-pipe connection 19 with a damper-regulator 20, the movable element of which has suitable connection, typified by a cord 21, with a 95 suitable draft-adjuster, typified by weighted

damper 22 in the fan-belt. As the boiler-damper regulator 20, as by detachable links 31 engaging a pivoted lever 32 operatively attached to the cord 21 of the damper regulator, the fuel-feeding rate may be varied harmoniously with changes of pressure conditions. 70

5 pressure resulting in opposite operation of the damper. Further, the fan 17 is indicated as driven from an electric fan motor 23, the speed of which is variable, and the fan-motor speed is controlled by a suitable rheostat 24 which, in turn, is worked in response to steam pressure, supplied through pipe 25 to a pressure-responsive rheostat actuator 25' of any suitable construction. Thus in general, air supplied to the stoker is preferably automatically variable harmoniously with steam-pressure changes.

10 Each feed-ram structure, generally indicated at 16, Fig. 2, involves a reciprocating plunger 26 working in a hopper-equipped cylinder-structure 26^a and each plunger is to be driven by its individual electric motor 27 or 27', as diagrammatically illustrated in Fig. 1. Each excursion of the ram-plunger, either on its feed stroke or its return stroke, involves starting and stopping its respective electric motor and periodicity of the motor-starting operation determines periodicity of operation of the associated ram. For controlling the periodicity of operation of each 15 ram-actuating motor, I associate with each motor an individual timing-switch mechanism, 28 or 28' as specifically illustrated in Figs. 7 to 10, such mechanism including an electric circuit-controlling switch in the power circuit of its respective motor and mechanical switch-operating devices which are variably operable to vary the intervals between switch-movement and thereby vary the periodicity of operation of the associated ram.

20 Where it is desired that periodicity of ram operation, and consequently the rate of fuel feeding, shall be varied in harmony with steam-pressure variation, this may be accomplished by connecting mechanical parts of the timing switch structures 28 and 28' to be variably worked from the same pressure-responsive devices that control the air-supply. As will more fully appear from the specific description hereinafter, rate of rotation of the power-wheel 54 of each time switch mechanism partially controls the periodicity of ram-operation, and by driving these pulley wheels 54 by belting connections 25 from the shaft of the stoker-fan 17, fuel feeding rate may be augmented harmoniously with increase of air supply, and vice versa. Likewise, (as will more fully appear) oscillation of a lever arm 30 of the time-switch mechanism 28 will vary the number of revolutions of the power-wheel 54 that will occur between successive operations of the motor-controlling switch, and by connecting all of these arms 30 of the respective timing-switches 28 and 28' with the

31 engaging a pivoted lever 32 operatively attached to the cord 21 of the damper regulator, the fuel-feeding rate may be varied harmoniously with changes of pressure conditions. 75

Referring to Figs. 2 to 6, the mechanical screw-drive of the ram-plunger 26 is so constructed that its driving connection with its electric motor 27 will be automatically broken at each end of the plunger-excursion, leaving the electric motor free to continue in idle rotation without injury to any of the parts. The rear end of the plunger 26 is hollow, for reception of the operating screw 38, 80 and is provided with a fixed reducing-collar 36 at its open, rear end for cooperation with the elongated traveling nut 37 which rides on and along the screw-shaft. The hollow plunger, kept practically closed by the collar and nut, may be grease-filled and the screw is provided at its end with a grease-stirring plate 39 having a suitably angled end 39'. The collar 36 is loosely embraced, for some axial lost motion, between two abutments on the elongated nut 37, these abutments being a ring 40 on the inner end of the nut and a head-structure 41 near the outer end of the nut. Consequently, as the nut 37 travels along its screw-shaft 38, in either direction, it will carry with it the ram-plunger 26 at first taking up the lost-motion that is intentionally left between the collar 36 and the nut-carried abutments 40 and 41. In order that the screw-shaft 38 shall be caused to rotate first in one direction and then in the other, its driving electric motor 27 is reversible, and such motor may be mounted directly on the frame work of the ram and connected with the screw shaft by simple belt and pulley power-connections 43. Referring to Fig. 2, it will be observed that when the electric motor 27 is energized to drive the ram plunger on its feed stroke, (i. e. leftwardly in the drawing), the motor will "pick up" under minimum, almost-negligible load, since the feed nut will have to travel along the feed screw 38 far enough to bring head 41 into contact with collar 36 before the motor-driven screw begins to propel the ram-plunger 26 along the feed-cylinder. 90

10 Such "pick up" under minimum load is very desirable, and it will occur also on the return stroke, when the motor is reversed. 105

110 Of course the feed-nut structure 37 will turn idly in unison with the screw, rather than travel axially along the screw and propel the ram-plunger, whenever the nut is left free for such idle rotative movement, and I utilize this characteristic by automatically controlling the freedom or the restraint of the nut in this regard. The nut-head 41, which fits easily in the cylindrical body structure 26^a of the ram, carries a series of radially-arranged gravity pawls 45 which 115

are radially shiftable in notches or pockets formed in the head 41. Side-rings 46 fastened to the main portion of the nut head, keep the pawls laterally in position and also 5 act as stops for the lugs or feet 45' of the pawls to limit radially-outward displacement of the pawls. Any pawl 45 may, when in bottom position as illustrated in Figs. 2 and 10, engage in a slot 48 which extends longitudinally along the bottom of the cylinder-structure 26^a, the side walls of the slot forming abrupt shoulders (except at the slot ends) to prevent rotation of any pawl that engages therewith and so to hold the feed 15 nut against idle rotation. At each end of the range of travel of the feed nut 37, however, one wall only of the slot 48 is beveled, as respectively indicated at 49 and 49' to form pawl-escapeways, these two bevels 20 being oppositely arranged as shown in Figs. 4 and 5 so that when any active pawl 45 reaches either end of its range of excursion along the slot 48 it encounters a beveled escape surface across which the pawl may 25 readily slip rotatively (incidentally being cammed back into its recess in the head 41) thereby enabling the drive-nut 37 to idle pending reversal of direction of movement of the screw-shaft 38. Since the squared 30 shoulder of the slot forms the side-wall portion opposite each such escapeway, it will be apparent that when the direction of rotation of the screw-shaft is reversed, after the idling operation of the nut above described, 35 the pawl 45 first approaching the slot 48 will engage such squared side-wall of the slot 48 and thereupon the nut will start on its return travel.

It will now be apparent that the screw 40 drive construction above characterized is quite importantly related to the fact that the screw is driven by an electric motor and to the further fact that the periodicity of operation of said motor (and consequently of 45 the screw 38) is adjustably variable. Not only does the electric motor "pick up" under minimum load, but the duration of its run in either direction of rotation may be considerably longer than the brief time required 50 for causing the ram-plunger to effect its powerful, quick excursion in either direction, the excess duration of motor-operation merely resulting in the idle rotation of the nut in unison with the screw-shaft. This 55 characteristic is utilized in the illustrated embodiment of my invention, where the time-switch mechanism next to be described occasions varying duration of motor operation, with a minimum duration greater than 60 the time required for the motor to drive the nut 37 on a single or uni-directional excursion.

Referring to Figs. 7 to 10, the electrical reversing-switch arrangement for the motor 27, incorporated with the time switch mech-

anism 28, may be of simple construction. Two switches are provided, each having two blades connected for unison movement by a fiber block 55 surmounted by sloping wear-plate 55'. One pair of blades 56 and their stationary contacts 56' control one circuit for the motor; the other contacts 57, 57' control the reversing circuit. Cams 51 and 52 angularly spaced upon a rotor 53 will operate the respective switches alternately and sequentially, holding each switch closed for a period longer than that required for driving the ram-plunger 26 on its feed stroke. Thus, during each cycle or single rotation of rotor 53, motor 27 is run in one direction, 70 stopped, reversely run and stopped again. 75

The constantly driven power-wheel 54 for the time-switch mechanism runs loosely upon the shaft 58 of the rotor 53, but to such shaft 58 a ratchet wheel 59 is securely fixed as by a key 59', and the loosely-running power-wheel 54 carries a pawl 60 which is gravity-urged towards said ratchet wheel 59, as best shown in Fig. 10. The pawl 60 can engage the ratchet 59 only when the pawl-lifting pin 61, near the nose of the pawl, drops into a peripheral recess 62 of a shielding 63 which is fastened by screws 64 to the fixed frame 65 of the switch mechanism. The "arc" or circular length of the recess 62 therefore determines the angular displacement that the pawl 60 can give to the ratchet-wheel 59 (and consequently the rotor 53) during a single rotation of the power-wheel 54, or otherwise stated, determines the 90 number of rotations of the power wheel 54 necessary to effect a complete cycle of rotation of the rotor 53. Obviously, varying the rotative speed of the power-wheel 54 will modify the periodicity of operation of the 95 timing mechanism, but I also provide for modification of said periodicity by varying the effective length of said recess 62. 100

70 indicates a complemental shield-plate having a peripheral recess. The hub of 110 such plate 70 extends through the open center of the shield-ring and is screwed, as at 75, to an adjusting lever 71 which is manually movable through a suitable arc of adjustment, thereby to set the two recessed members 63 and 70 for a given effective length of the recess 62. The heretofore-mentioned lever 30, which is mounted to be rocked about the axis of the shaft 58 and is operatively connected to the damper regulator 20 so as to be moved in accordance with changes in steam pressure, is also connectible with the adjustable shield-plate 70, so that movement of said lever 30 may alter the effective length of the pawl-controlling 120 recess and thereby vary the periodicity of operation of the motor-controlling switch. As shown in Fig. 8, such lever 30 extends alongside of lever 71 and it has a segmental end 30' provided with a series of notches 125 130

any selected one of which may be engaged by a spring-latch 73 carried by the lower end of the manual-adjustment arm 71. Therefore, with the automatically-movable lever 30 standing in any given position (say the neutral position shown in Fig. 10) the manual adjusting arm 71 may be rocked with respect to it and engage with any one of the notches 72, thereby to vary the effective length of the shield-ring recess 62; yet if the lever 30 be automatically moved to one side or the other of its stated initial position, the effective length of such recess 62 will be varied accordingly, since the automatically-operated lever 30 will carry the manual-adjustment lever 71 along with it. To enable this automatic adjustment to be dispensed with on occasion, lever-segment 30' is provided with a spring lock 74 which 20 may be engaged in a recess of the switch frame 65.

In brief résumé of specific operation, it will be apparent (see Fig. 2) that when screw 38 is rotated in one direction by the reversible electric motor 27, the nut-structure 37 will travel along the screw from the position shown in Fig. 2 as long as one of the nut-carried pawls engages the squared edge of the slot 48 in the bottom of the ram-cylinder 26^a. The motor will start under practically no load, while the nut-structure 37 is taking up the lost motion to bring its head 41 into engagement with collar 36 of the ram-plunger. When the nut has carried the ram-plunger through its feeding stroke, the theretofore-restrained pawl 45 comes opposite the beveled surface 49' (Fig. 5) and the nut-structure 37 becomes free to rotate idly in unison with the screw 38, pending stoppage and reversal of the motor 27. Motor stopping and starting, in alternately reversed directions, is effected by the reversing switch arranged in the motor circuit and forming part of the automatic timing switch device 28 shown in Fig. 7 to 10. Each turn-over of the rotor 53 effects a cycle of operation of the reversing switches, the sequence of operations being prescribed by the arrangement of cams 51 and 52. Each such cam will hold its switch closed for a time (as a minimum) longer than the time required to cause a motor-driven stroke of the ram. Excess time merely causes idle rotation of the motor after the pawl-mechanism on the screw-drive has broken the operative connection between the motor and the ram-plunger 26. The periodicity of operation of the time switch mechanism is variable, being manually settable and also automatically variable in accordance with variations in steam-pressure. The ratchet and pawl mechanisms 59 and 60 intervening between the power-driven pulley wheel 54 and the rotor 53 may be varied in operation by 65 adjusting the pawl-controlling shield-plate

70 with respect to the relatively fixed shield-ring 63 to alter the effective length of the shield-recess 62 and vary the number of revolutions of the pulley wheel 54 that are required to effect a single rotation of the 70 rotor 53. Such adjustment may be manually made by shifting the hand lever 71 with respect to the notched sector 30', shown in Fig. 10. The latter sector, 30' may be latched in fixed position by latch 74 or it 75 may be connected for automatic movement by the damper regulator 20 through the cord 21, the lever 32 and detachable link 31. Also the rate of rotation of the pulley wheel 54 of the switch mechanism may be changed 80 in response to changes of stem-pressure condition, as by driving said wheel from the shaft of the blast fan 17, the speed of operation whereof is in turn controlled by the pressure-responsive device 25' working the 85 controlling rheostat 24 of the electric motor 23 which drives said fan.

I claim:

1. In a screw-drive for an underfeed stoker ram, a plunger, a screw, means to rotate the screw in either direction, a nut coacting with the screw and plunger to carry the plunger in either direction through a definite range of movement when restrained against idle rotation with the screw, and restraining means controlling said nut. 90

2. In a screw-drive for an underfeed stoker ram, a plunger, its shell, a screw, means to rotate the screw in either direction, 100 and a nut coacting with the screw, the shell and the plunger to carry the plunger in either direction through a definite range of motion and idly to turn with the screw during excessive rotation of the screw. 105

3. In a screw-drive for an underfeed stoker ram, the combination with a plunger and a plunger-operating screw, of an electric motor to rotate the screw, a nut on the screw having lost-motion connection with the plunger, and means to cause said nut to travel along the screw through a definite range of motion and idly to turn with the screw during excessive rotation of the screw. 110

4. In a screw-drive for an underfeed stoker ram, the combination with a plunger and its shell having an internal longitudinal shouldered guideway with oppositely extending beveled escape-ways opening to opposite ends of the guideway, a feed-screw, means to rotate said screw in either direction, and a nut upon the screw rotatable with respect to and movable longitudinally with the plunger, said nut having a pawl to engage said guideway and said pawl being movable with respect to the nut to permit the nut to turn idly with the screw when said pawl encounters a beveled escape-way. 120

5. Driving means for an underfeed stoker 125

- ram comprising, in combination, the ram-plunger, a screw, a reversible electric-motor to operate the screw in either direction, automatically-operable reversing-switch mechanism for running said motor in opposite directions, each normally for a longer period than is necessary to move the plunger through a single excursion, and automatic means for breaking the driving connections 5 between said motor and the ram-plunger to permit said motor to idle when said plunger reaches the end of its excursion.
6. Driving means for an underfeed stoker ram comprising, in combination, a ram-plunger, a reversible electric motor to operate said plunger in opposite directions, and power transmitting connections between said motor and said plunger having automatic means for breaking said power connections 10 and permitting said motor to run idly when said plunger reaches either end of its reciprocation.
7. Driving means for an underfeed stoker ram comprising, in combination with a ram-plunger and shell, a screw, a reversible electric motor to operate the screw in either direction, automatically operable reversing-switch means for running said motor in opposite directions, each normally for a greater period than is necessary to move the plunger through a full excursion, and a nut, coacting with the screw, the shell and the plunger to carry the plunger in either direction through a definite range of motion 15 and idly to turn with the screw during excessive rotation of the screw.
8. Driving means for an underfeed stoker ram comprising, in combination, a ram-plunger, and shell, a screw, a reversible electric-motor to operate said screw in either direction, automatically operable reversing switch means for running said motor in opposite directions each normally for a greater period than is necessary to move the plunger through a full excursion, and a nut coacting with the screw, the shell and the plunger to carry the plunger in either direction through a definite range of motion and idly to turn with the screw during excessive rotation of said screw, said nut having lost-motion connection with the plunger to permit said motor to "pick up" before imposition of the plunger-load on the motor. 20
9. Driving means for an underfeed stoker ram comprising, in combination, a ram-plunger, an electric motor, plunger-driving connections between said motor and said plunger, means for breaking said connections automatically when the plunger reaches either end of its stroke, a cyclically operable switch in the motor circuit for starting and stopping said motor to control the frequency of reciprocation of said plunger, power supply means for operating said switch, and means for varying the periodicity of operation of said switch, to vary the feed-rate of the ram. 25

DALLAS F. GRAHAME.
